UNITED STATES PATENT OFFICE.

JAMES B. HAUSE, OF CLINTON, MICHIGAN.

ICE-HARVESTING MACHINE.

SPECIFICATION forming part of Letters Patent No. 723,774, dated March 24, 1903.

Application filed May 17, 1902. Serial No. 107,824. (No model.)

To all whom it may concern:

Be it known that I, JAMES B. HAUSE, a citizen of the United States, residing at Clinton, in the county of Lenawee and State of Michigan, have invented new and useful Improvements in Ice-Harvesting Machines, of which the following is a specification.

This invention relates to ice-harvesting machines; and the object of the invention is to provide an improved machine of this character capable of cutting the ice simultaneously in transverse direction—that is to say, into blocks.

The improved machine includes a main cutter and an auxiliary cutter, the main cutter being adapted to cut the ice longitudinally of the machine, so as to form strips, while the auxiliary cutter cuts through these strips to form the blocks, which may be suitably disposed of. The frames for both cutters are mounted for oscillation, that of the main cutter being adjusted by hand, while the one for the auxiliary cutter is lowered and raised automatically during the advance of the machine, such frame of the auxiliary cutter being so mounted that it has a movement relatively to the frame of the machine, whereby when the auxiliary cutter is in the ice the machine can advance without necessitating the stoppage of either of the cutters, which consist, preferably, of rotary saws, the same being continuously operated during the action of the machine. Simple and efficient mechanism is provided for operating the two cutters or saws in unison and for raising and lowering the frame of the auxiliary saw at proper times and for also propelling the machine either forward or backward or for quickly stopping said machine.

The invention includes other objects and advantages which with the foregoing will be set forth at length in the following description, while the novelty thereof will form the basis of the claims succeeding such description, and such invention is clearly represented in the accompanying drawings, forming a part of the specification, and in which—

Figure 1 is a top plan view of an ice-harvesting machine including my invention. Fig. 2 is a side elevation as seen from the side thereof, carrying the auxiliary saw. Fig. 3 is a front elevation of the same. Fig.

4 is a sectional side elevation of part of the propelling mechanism. Fig. 5 is a sectional front view of the same. Fig. 6 is a diagrammatic side elevation of an arrangement of driving-chains and their supports. Fig. 7 is a detail in side elevation of a guide-wheel and its controlling means. Fig. 8 is a detail in sectional side elevation of a means for shifting the machine transversely of its normal direction of movement. Fig. 9 is a perspective view of a connecting-rod and certain coacting parts. Fig. 10 is a sectional side elevation of a part of the frame of the auxiliary cutter and certain mechanism for securing the movement of said frame relatively to the frame of the machine. Fig. 11 is a top plan view of the same. Fig. 12 is a sectional front elevation of said auxiliary-cutter frame and the means for automatically oscillating the same. Fig. 13 is a sectional inside elevation of said last-mentioned frame and a cross-bar constituting a track for the same, together with certain adjacent parts. Fig. 14 is a sectional elevation of said cross-bar and bracket on the auxiliary frame.

Like characters refer to like parts in all the figures of the drawings.

The improved machine carries mechanism for propelling the same along the ice and working automatically will cut the ice into separate blocks of uniform size ready for storage without the use of any other saw, ax, or spud and without the aid of any operator, with the exception of one at the end of the ice-field, who will be required to stop the machine and set it over sidewise the width of one cake and reverse the propelling mechanism, as will hereinafter appear at length.

The machine includes in its construction a frame of some suitable construction, the one represented being denoted in a general way by 15 and having on its upper side the deck or platform 16, which is adapted to sustain a motor of some suitable kind for propelling the machine and for operating the cutters and which deck or platform has a narrow extension 17, upon which the operator can stand, so as to be within reach of the various governing-levers.

The frame 15 has on the under side thereof, crosswise of the same, the axles 18 and 19, the axle 18 being at what I shall for conven-

ience term the "front" of the machine, for, as will hereinafter appear, said machine is adapted to travel oppositely upon the ice without turning.

5 The axles carry at their ends traction-wheels 20, peripherally roughened, so as to secure the proper action of the same.

The invention is of course not limited to the construction thus far described and hereinafter set forth and as illustrated fully in the accompanying drawings, for many variations may be adopted within the scope of my appended claims.

I will now describe a mechanism which is 15 adapted for propelling the machine along the ice and for securing reversals in direction of movement thereof or complete stoppage of the same.

The motor is mounted on the platform 16. 20 I have not deemed it necessary to represent the same, for it may be of any suitable type.

The numeral 21 indicates the main shaft, or it may be the motor-shaft, from which the propelling mechanism derives its motion, and, 25 as will be hereinafter pointed out, the saw-actuating mechanism is also operated from such shaft.

Standards or uprights 22 rise from the frame of the machine and carry in suitable bearings 30 the cross-shaft 23, provided at its inner end with a sprocket-wheel 24, Figs. 1 and 6, connected by a sprocket-chain 25 with the sprocket-wheel 26 on the said main shaft 21. To this cross-shaft is feathered for sliding 35 movement a friction-roll 27, to which is suitably non-rotatably connected the bail or yoke 28, the hand-lever 29 being pivotally connected with said bail, such lever being suitably fulcrumed to the framing and its handle 40 being within easy reach of an operator on the platform extension 17. The friction-roll is adapted to engage the working face of the friction-disk 30, carried at the upper end of the vertical spindle 31, it being understood 45 that the horizontally-disposed friction-roll is adopted to rotate the disk.

The spindle 31 has fast on its lower end the bevel-gear 32, meshing with a corresponding bevel-gear 33, Figs. 4 and 5, loose on the forward axle 18, the bevel-gear 33 having an integral pinion 34, meshing with a fixed and larger pinion 37 on a counter-shaft 37', also carrying a small fixed pinion 37", meshing with a larger and fixed pinion 38' on the said 55 front axle 18, said axle being connected by sprocket-gearing (denoted in a general way by 38) with the rear axle, so that such axles can be thereby driven in synchronism.

When the friction-roll 27 is in the position 60 illustrated in Fig. 5, the machine will be driven forward at a relatively high speed, and by moving the roll nearer the axis of the disk the velocity of the machine will be reduced, and the same can be stopped by moving the roll to the dead-center of the disk, while its motion can be reversed by putting the roll across such dead-center.

The train of gearing hereinbefore described constitutes a simple means for properly regulating the speed of the machine along the ice. 70

While the movement of the machine can be arrested by the roll 27, which can be moved sidewise along its supporting-shaft 23 by the hand-lever to the dead-center of the disk 30, still I provide other means for this purpose, 75 the roll being shifted out of contact with its disk for this purpose, as will now be set forth.

The shaft 23 is sustained by bearings 39, suitably mounted for vertical sliding movement against the inner faces of the standards 22. Links 40 are pivoted to said slideable bearings and are likewise eccentrically connected to the ends of the shaft 41, also supported by said standards and situated above 85 the other shaft. The said upper shaft is provided with a hand-lever 42, Figs. 4 and 5. By swinging the hand-lever rearward the friction-roll 27 through the intermediate connections is lifted off the upper face of the disk, 90 so as to stop the machine, provided the machine be moving. When the friction-roll is free of its disk, the former can be moved along its shaft 23, so as to change the direction of movement of the machine, if necessary. 95

When the machine is traversing the ice, the friction roll or wheel is in contact with its disk; and to assure the proper engagement of the same the hand-lever 42 is weighted, 100 so as to hold the roll firmly against its disk. By swinging the lever rearward the roll is lifted clear of the disk and is then moved a sufficient distance until its center of gravity has crossed a vertical line intersecting its 105 center of motion, at which point it is adapted to abut against a suitable stop, as 43, on the framework, Fig. 3, such stop consisting in the present case of a nut carried on one end of a shaft hereinafter more particularly described. 110

As will hereinafter appear, the machine includes main and auxiliary saws, and before they are put into action I mark a line across the ice and will now describe a suitable marking device for obtaining this result. 115

Viewing the machine from what I have termed the "front," it is provided at its left with a peripherally serrated and toothed marking-wheel 44, fixed to the short shaft or mandrel 45, connected by pulleys and belts with a power-shaft, hereinafter described, so that when the machine is driven along the ice and such shaft is rotated the said marking-wheel will make a cut in parallelism with the direction of movement of the machine and which cut is made as straight as it is possible for the operator to make it. After the marking cut or groove has been made, and such cut or groove is a comparatively shallow one, guide-wheels 46 are let into said cut during the return trip of the machine, and on such return trip the saws for forming the ice into blocks are put into action. 125 130

The guide-wheels are in alinement with each other longitudinally of the machine and are separated transversely of the machine a distance agreeing with the width of the strips 5 of ice cut by the main saw. Said guide-wheels are carried by the swinging brackets 47 at the ends of the frame 15, and links 48 are connected with the respective brackets and also with hand-levers 49, pivoted at their 10 lower ends in proximity to each other to the side bars of the frame 15, (see Fig. 7,) and notched plates, as 50, are adapted to coöperate with the respective levers to hold them in their two positions.

15 With the parts in the positions shown in Fig. 7 the guide-wheel 46 is adapted to enter the groove previously made in the ice by the rotary marking-wheel 44. At the end of the movement of the machine in one or the other 20 direction the machine is shifted laterally; but before this can be done it is necessary to lift the guide-wheels out of the marked or guide groove. This action can be accomplished by swinging the hand-levers 49 outward, and 25 when the machine has been moved the requisite distance sidewise the two guide-wheels 46 will be lowered into the guide-groove just formed by the machine and the latter will be moved in a direction opposite that last followed.

30 It will be seen that the plates 50 are provided with two notches, Figs. 1 and 7, to hold the two levers 49 in their two positions, respectively. The first thing that takes place, 35 therefore, on the initial movement of the machine is the formation of a guide-groove by the marking-wheel 44, and on the return of the machine the guide-wheels 46 will be lowered into said groove, so that as the machine 40 is propelled such guide-wheels prevent lateral motion of said machine and hold it to a straight course.

I will now describe the means shown for shifting the machine sidewise after the conclusion of a course thereof. Pivot-bolts, as 45 51, extend vertically through the end bars of the frame, substantially midway of the lengths thereof, and outwardly-extending levers 52 are pivoted to the upper ends of such bolts and 50 are fulcrumed at the middles to posts or columns 53, which terminate at their lower ends in feet or bases 54, adapted to slide along the ice and suitably braced. (See Fig. 8.) By 55 lowering the outer or free ends of the levers 52 the frame 15 can be lifted, and by moving the same horizontally the said frame can be carried to the left or until the guide-wheels 46 are above the previously-made guide-groove, at which point the said wheels will be 60 lowered into said groove and the machine propelled to follow a course opposite to that last taken, and during such period of operation the marking-wheel 44 will make a second groove. Subsequently the main or longitudinal saw will be let into the marked groove, 65 which causes the making of a perfectly straight cut through the ice.

My improved machine includes a plurality of saws—a main saw and an auxiliary saw—the same being capable of simultaneous operation and the main saw cutting the ice longitudinally of the same, while the auxiliary one cuts the ice crosswise of the main one, so that such ice is cut up into blocks, and in the present case each saw is continuously rotated, 70 as will hereinafter appear, and I will now describe the main-saw mechanism and its operation. The main saw is denoted by 55, and it is suitably fixed to a shaft 56, rotatably mounted at the outer end of a rocking frame 57, which is 75 sustained for oscillation by the shaft 58, connected by belt-and-pulley mechanism with the saw-shaft. The auxiliary or crosscutting saw, as will hereinafter appear, is also driven by power-transmitting mechanism operable 80 by said shaft 58. Said shaft 58 is provided with a sprocket-wheel 59, connected by sprocket-chain 60 with the sprocket-wheel 61 on the motor-shaft 21. The shaft 58 is stopped and started through the agency of a clutch 62, 85 the one shown being of the friction type and its movable member being operated by the hand-lever 63, the handle of which is within convenient reach of the operator. In Fig. 3 the movable clutch member is shown as being 90 out of contact with its companion, so that both saws are held at rest during this relation; but when put into contact therewith the two saws will be rotated, so as to cut the ice. It will be understood that the movable clutch 95 member is splined to its shaft, while its mate is loose thereon, but is rigid with the sprocket-wheel 59, the prime pulley 64 of the main-saw-rotating mechanism being also fixed to said shaft. A rock-shaft 65 is supported by the 100 standards 22, Figs. 1, 2, and 3, and is provided at its outer end with a crank-arm, provided in turn at its outer end with a link 67, jointed to the rocking main-saw frame 57. A lever 68 is fastened to the rock-shaft 65, and it carries a 105 detent 69, coöperative with the fixed toothed sector 70, the detent by engaging the teeth of the sector serving to hold the lever, and thereby the main-saw frame, in an adjusted position. The said lever 68, which, like the other 110 levers, is within easy reach of the operator, carries means for operating the detent 69 thereon, and such lever when manipulated serves, through the intermediate mechanism, for raising and lowering the main-saw frame 115 57, to thereby move the main saw out of and into the operative position.

The marking-wheel 45 has its shaft supported by a rocking frame 71, oscillatory on the power-shaft 58, and which frame is connected, by means substantially like those just described, with a lever 72, which coöperates with a fixed toothed sector through a detent carried by said lever, so that the marking-wheel frame can be also raised or lowered, it being apparent that such last-mentioned frame is elevated when the machine is being shifted sidewise and is then lowered when the machine has been moved the desired lateral distance.

The auxiliary cutter or saw is denoted by 73, and its shaft 74 is supported for rotation at the outer end of the frame 75, carried for oscillation by the shaft 76 on the upper side 5 of the machine, and said frame has a sliding movement along said shaft, as will hereinafter appear. The auxiliary-saw frame 71 carries a shaft 77, provided at its ends with bevel-gears 78, the outer one of which meshes with 10 a similar gear 79 on said auxiliary shaft, while the inner one of which meshes with a like gear 80 on the longitudinal shaft 76, such gear 80 having a key (not shown) fitted into the groove or channel 81, extending lengthwise 15 of said longitudinal shaft 76. By reason of this construction the auxiliary saw can be continuously rotated while the auxiliary-saw frame is being moved back and forth on the machine, the bevel-gear 80 having a sliding 20 movement with such frame. The longitudinal shaft 76 is provided at its forward end with a bevel-gear 81^a, meshing with a similar bevel-gear 82 on the counter-shaft 58, so that on the rotation of the latter the auxiliary 25 saw will, through the intermediate connections just described, be rotated.

The mechanism for raising and lowering the auxiliary or crosscutting saw frame 75 is automatic and is operated from one of the 30 axles, or the propelling mechanism for such operation need only take place during the propulsion of the machine.

The longitudinal shaft 76 loosely carries the rocking levers 83, the arms of which 35 extend angularly from said shaft, such angle-levers being separated a suitable distance and their outer ends being rigidly connected by the cross-bar 84, Figs. 1, 12, and 13, said cross-bar constituting a track for supporting 40 for traveling movement the slidable and oscillatory auxiliary-saw frame 75 and the latter being provided with antifriction-rolls 85, bearing at suitable points against the upper and lower sides of the cross-bar or track 84, 45 Fig. 13.

The inner arms of the angle-levers 83 are jointed to the links 86, depending therefrom, and likewise united to crank-pins 87 on the crank-disks 88 on the shaft 89 in parallelism 50 with the longitudinal shaft 76. The parts are so arranged that on each rotation of the crank-disks the auxiliary-saw frame is given a complete oscillation, so as to cut the longitudinal strips of ice into blocks.

55 The shaft 89 has a fixed pinion 90, adapted to coöperate with a mutilated gear 91, the ratio between the gears 90 and 91 being a one-to-two one, so that when the mutilated gear makes a half-rotation the pinion will make a 60 complete rotation. The mutilated gear 91 is carried by a shaft 92, and its teeth are omitted on half the periphery thereof, so that when the plain portion thereof is contiguous to the pinion the auxiliary-saw frame will not 65 be oscillated, whereby such frame can be moved sidewise without affecting the proper action of the parts. The mutilated-gear shaft

is provided at its forward end with a bevel-gear 93, meshing with a coöperating gear fixed on the cross-shaft 94, the latter being connected by a train of gears 95 with the forward axle 18 and the first gear 95' of said train being loose on the shaft 94. The gear 95' is normally coupled to its shaft by the clutch 94', by operating the shipping-lever 96' of which 75 the automatic operation of the auxiliary-saw frame can be stopped.

It will be understood that as the machine is propelled along the ice the auxiliary-saw frame 75 is oscillated to first cause the auxiliary saw to enter and then to leave the ice. As the auxiliary saw is let into the ice the machine will be traveling forward, and by reason of the fact that the auxiliary-saw frame is slidable longitudinally of the machine the 85 latter can be moved forward while the auxiliary saw is making its cut, and when such cutting operation is concluded the said auxiliary-saw frame will be moved forward to its initial position, as shown, for example, in 90 Fig. 2.

I provide mechanism for sliding the auxiliary-saw frame along the machine of such a character that it is inefficient as a power-transferring factor while the auxiliary saw is 95 cutting the ice, but which is adapted to shift such frame relatively to the frame of a machine after a cut has been made, and such mechanism will now be described.

The shaft 94, which it will be remembered 100 is driven from the forward axle 18, carries a fixed gear 96, Fig. 1, meshing with a fixed pinion 97 on the shaft 98. The shaft 98 carries a pair of sprocket-wheels 99, arranged in parallelism on the said shaft and adapted 105 to respectively receive sprocket-chains 100, which also pass around the sprocket-wheels 101, fixed to the short shaft 102, the parts being so arranged that the upper runs of the parallel chains will be operated in a direction 110 opposite to that followed by the machine. For example, when the machine is traveling forward, as shown by the arrow in Fig. 1, the upper runs of such chains or belts will be moved to the direction of the arrow in Fig. 115 10. The connections between the chains and forward or driving axle 18 are such that the speed of the chains equals that of the machine. A pin 102^a extends through alined 120 links of the chains 100 and is suitably secured thereto, so as to follow a circuit while the machine is making a forward and backward course on the ice. By employing two chains the pin is held against lateral motion during the operation of the machine. A link 103 is 125 pivoted to the pin 102 and is likewise connected with the connecting-rod 104, guided in a horizontal direction and having at its rear end a bifurcated portion 105, adapted to straddle one of the sides of the auxiliary-saw 130 frame 75, the branches of the bifurcation carrying antifriction-rolls 106, serving their usual function.

It will be remembered that the surface

speed of the endless chains 100 is the same as that of the machine and that the upper runs of the said chains travel in a direction opposite that of said machine, so that while the 5 machine is advancing a given point on the upper horizontal run of the chain will be perpendicular to a fixed point on the ice. When, however, such given point on the chain passes to the lower run, it will move in the direction 10 of movement of the machine and at a speed twice that of the machine relative to such fixed point, so that the auxiliary-saw frame, which is controlled by the said chains, will when the auxiliary saw has been taken from 15 the ice after a cross-cut be returned to its initial position at relatively an accelerated velocity.

In Figs. 10 and 11 the endless chains 100 are shown as occupying their primary positions, while the same relation follows with 20 respect to the auxiliary-saw frame 75 in Fig. 2.

With the machine moving forward in the direction shown by the arrow in Fig. 1 the 25 upper runs of the chains 100, through the hereinbefore-described connections, will be carried rearward, and while the pin 102 is moving along the upper runs of the said chains it remains in perpendicular alinement with a 30 fixed point on the ice, and while the link 103, rod 104, and auxiliary frame 75 are moving relatively to the frame 15 of the machine they have no movement longitudinally of the machine relatively to the ice, and it is during 35 this period that the auxiliary-saw frame 75 is oscillated to carry the auxiliary saw 73 into and from the ice, as previously described, to make a cross-cut, it being understood that the saw is being continuously rotated. At 40 about the time the auxiliary saw leaves the ice the pin 102 will have reached the lower horizontal run of chains 100, so that such pin will be carried forward at a speed twice that of the machine relatively to a fixed point on 45 the ice, the connecting-rod 104, through the agency of the intermediate link 103, being thrust forward at the same relatively increased speed and serving to rapidly return the auxiliary-saw frame to its primary position. The same operation of the chains will 50 of course take place when the machine is being propelled rearward.

The parts are so timed that at the point the plain or non-toothed portion of the mutilated 55 gear 91 is opposite the pinion 90 the auxiliary-saw frame 75 is being given its accelerated forward motion, and thereby the said frame is prevented from oscillating, and at the proper moment, or when such auxiliary- 60 saw frame is in its primary position, the teeth of such mutilated gear will mesh with the pinion to oscillate said auxiliary-saw frame. The parts are so related that the mutilated gear 91 will be in position to mesh with the 65 teeth of the pinion 90 at the proper time, so as to secure the desired intermittent action of the oscillatory saw-frame. A bail 107 has

its branches pivoted to suitable uprights on the frame, and such branches have depending rods at their outer ends secured at their 70 lower extremities to the cross-bar on track 84. Said bail carries at its inner end a counter-weight 108, adapted to rest against rubber or like buffers 109 on the block 110. When the auxiliary-saw frame 75 is lowered, as previously set forth, the said weight will be lifted and will be lowered into contact with the said buffers on the elevation of said auxiliary-saw frame. The purpose of said weight 108 is to 75 counterbalance the frame carrying the same, 80 so that the power necessary to operate such frame is reduced to a minimum.

The auxiliary saw 73 does not, as hereinbefore described, separate the blocks from each other, this operation being secured by a 85 wedge operative with said auxiliary saw and which I will now describe. The shaft 74 of said auxiliary saw, Figs. 1, 2, and 3, has a disk 111, concentric with the auxiliary saw and adapted to fit flatwise against said saw 90 and having beveled portion 112. The disk is adapted to enter the cross-cut with the auxiliary saw, and when the latter has entered a desired distance into the ice the beveled face of the wedge-disk is adapted to forcibly separate the blocks from each other when the ice is in the form of strips. In some cases this wedge-disk 111 could be dispensed with and the auxiliary saw after it left the cross-cut would leave the block connected with the 95 body of the ice by narrow necks at the inner corners thereof. These necks could readily be broken at a subsequent and independent operation. To prevent rebounding of the weighted lever or bail 107, I connect the outer 100 end of the same with a coiled spring 113, the same being also connected with the frame of the machine.

It is believed that the complete operation of the machine will be at once apparent from 110 the foregoing description. Briefly set forth, it is as follows: The machine will be run forward and then backward over the ice, it being shifted sidewise after each course, as previously stated, and when several guide or 115 marking cuts have been made by the marking-wheel 44 the main saw 55 on the next course will be lowered manually into the last cut, and when the machine is propelled forward the said saw will cut the ice longitudinally of the machine or in the direction of 120 travel thereof. During this period the auxiliary-saw frame 75 is being automatically rocked, as hereinbefore set forth, to carry the auxiliary saw 73 into and from the ice, it being understood that the saws are being both 125 continuously rotated. When the auxiliary-saw frame is lowered, the machine is moving forward, leaving the auxiliary-saw frame stationary relatively to the ice. When, however, 130 the said auxiliary-saw frame is elevated, it is slid forward on the machine to repeat the operation.

The complete operation just briefly out-

lined will be repeated while the machine is being moved forward and backward.

Having described the invention, what I claim is—

5. 1. In an ice-harvesting machine, a cutter, means for lowering said cutter toward and into the ice and then elevating the same, an endless belt, means for operating the belt at the same speed at which the machine is driven 10 along the ice, and connections between said belt and cutter for maintaining the latter in a fixed position relatively to the line of travel of the machine while said cutter is in the ice and for subsequently moving the cutter in 15 the direction of the length of travel of the machine.

2. In an ice-harvesting machine, a cutter, a frame for the cutter maintained for oscillatory and sliding movements of the frame of the machine, an endless belt, means for operating the belt at the same speed at which the machine is driven along the ice, and connections between the belt and the cutter-frame for maintaining the latter in a fixed position relatively to the line of travel of the machine and for subsequently sliding said cutter-frame along the machine-frame in the direction of said line of travel.

3. In an ice-harvesting machine, a cutter, means for lowering the cutter toward and into the ice and then elevating the same, an endless belt, the runs of which are horizontally superposed, means for operating said belts at the same speed at which the machine is driven 30 along the ice, and connections between said belt and cutter for maintaining the latter in a fixed position relatively to the line of travel for a given length of time, and for subsequently moving the cutter in the direction of the line of travel of said machine.

4. In an ice-harvesting machine, a cutter, a frame for the cutter mounted for oscillatory and sliding movements on the frame of the machine, means for automatically operating 45 said cutter-frame whereby the cutter will be carried toward and into the ice and then elevated, an endless belt, means for operating the belt at the same speed at which the machine is driven along the ice, and connections 50 between the belt and the cutter-frame for maintaining the latter in a fixed position relatively to the line of travel of the machine while the cutter is in the ice and for subsequently sliding said cutter-frame along the machine-frame.

5. In an ice-harvesting machine, a cutter, a frame for the cutter mounted for oscillatory and sliding movements on the frame of the machine, an endless belt the runs of which 60 are horizontally superposed, means for operating the belt at the same speed at which the machine is driven along the ice, a link connected with said belt, and a rod connected respectively with the link and cutter-frame.

65. 6. In an ice-harvesting machine, a cutter, a frame for the cutter mounted for oscillatory and sliding movement on the frame of the

machine, an endless belt the runs of which are horizontally superposed, means for operating the belt at the same speed at which the machine is driven along the ice, a link connected with said belt, and a rod connected with the link having a bifurcation, the branches of which are adapted to straddle 70 said cutter-frame.

75. 7. In an ice-harvesting machine, a cutter, a frame for the cutter mounted for oscillatory and sliding movement on the frame of the machine, a plurality of endless belts arranged side by side, the runs of which are superposed, a pin connecting said endless belts, a link united to the pin, a rod connected respectively with the cutter-frame and link, and means for operating said belts at the same speed at which the machine is driven along 80 the ice.

8. In an ice-harvesting machine, a cutter, a frame for the cutter, mounted for oscillatory and sliding movements on the frame of the machine, an endless belt, the runs of which are horizontally superposed, means for operating the belt at the same speed as the machine, connections between said belt and cutter-frame, a plurality of levers, a cross-bar, connecting the said levers and adapted to sustain 90 said cutter-frame in its sliding movements and a pair of disks having cranks, links connecting said cranks with said levers, a pinion co-operative with said disks, a mutilated gear for operating said pinion, and means for operating 95 said mutilated gear.

9. In an ice-harvesting machine, an oscillating cutter-carrying frame, an oscillatory track-carrying frame along the track of which the cutter-carrying frame is arranged to 105 travel, means for positively operating the track-carrying frame, and means for causing the cutter-carrying frame to reciprocate upon said track and for maintaining the same in a fixed position relatively to the ice for a given 110 time.

10. In an ice-harvesting machine, a cutter, a frame for the cutter, mounted for oscillatory and sliding movements on the frame of the machine, means for automatically oscillating 115 the said frame, said means including intermeshing gears, one of which is mutilated, a counterweighted lever and a track upon which said cutter-frame is adapted to slide, said track being connected with said counterweighted lever.

11. In an ice-harvesting machine, the combination of a main cutter arranged to cut the ice in the direction of the travel of the machine, an auxiliary cutter arranged to cut the 125 ice transversely to the main cutter, an oscillatory frame carrying the auxiliary cutter, an oscillatory track-carrying frame along the track of which the auxiliary-cutter-carrying frame is adapted to travel, means for positively operating the track-carrying frame, and mechanism for causing the said auxiliary-cutter-carrying frame to reciprocate upon 130 said track and for maintaining the same in a

fixed position relatively to the ice for a given time.

12. In an ice-harvesting machine, an oscillatory cutter-carrying frame, an oscillatory track-carrying frame along the track of which the cutter-carrying frame is adapted to travel, an endless belt, connections between the endless belt and said cutter-carrying frame for effecting the reciprocation of the latter and for also maintaining it in a fixed position relatively to the ice for a given time, and means for driving said endless belt at the same speed as the machine.

13. In an ice-harvesting machine, the combination of a shaft, a cutter-carrying frame arranged to oscillate upon said shaft, a track-carrying frame also oscillatory on said shaft and along the track of which said cutter-carrying frame is adapted to travel, means for positively operating the track-carrying frame, a driving member feathered to and slidable upon said shaft, a driven member supported by the cutter-carrying frame, a cutter rotative upon the latter, connections between the driven member and the cutter for actuating the latter, means for driving said shaft, and mechanism for causing the cutter-carrying frame to reciprocate upon said track and for maintaining the same in a fixed position relatively to the ice for a given time.

14. In an ice-harvesting machine, an oscillatory cutter-carrying frame, an oscillatory track-carrying frame along the track of which the cutter-carrying frame is adapted to travel, means for lowering the track-carrying frame and for maintaining it in its lowermost position for a predetermined length of time and for then elevating the same, and mechanism for causing the cutter-carrying frame to reciprocate upon said track and for maintaining the same in a fixed position relatively to the ice for a given time and while the track-carrying frame is in its lowermost position.

15. In an ice-harvesting machine, an oscillatory cutter-carrying frame, an oscillatory track-carrying frame along the track of which said cutter-carrying frame is adapted to

travel, means for positively operating the track-carrying frame, including a pair of meshing gears, one of which is mutilated, and mechanism for causing the cutter-carrying frame to reciprocate upon said track and for maintaining the same in a fixed position relatively to the ice for a given time.

16. In an ice-harvesting machine, a main cutter arranged to cut ice in the direction of the traveling machine, an auxiliary cutter, an oscillatory frame for carrying said auxiliary cutter, an oscillatory track-carrying frame along the track of which the first-mentioned frame is adapted to travel, mechanism for positively operating said track-carrying frame, an endless belt, connections between the belt and the said auxiliary-cutter-carrying frame for reciprocating the latter and for also maintaining it in a fixed position relatively to the ice for a given time, means for driving the belt at the same speed as the machine, and means for driving the two cutters in unison.

17. In an ice-harvesting machine, a cutter arranged to cut the ice in the direction of travel of the machine, a second cutter arranged to cut the ice crosswise of the other cutter, means for lowering the second cutter toward and into the ice and then elevating the same, an endless belt, means for operating the belt at the same speed at which the machine is driven along the ice, and connections between said belt and second cutter for maintaining the latter in a fixed position relatively to the line of travel of the machine while said second cutter is in the ice, and for subsequently moving said second cutter in the direction of the length of the travel of the machine.

In testimony whereof I have hereunto set my hand in presence of two subscribing witnesses.

JAMES B. HAUSE.
